(57) **CLAIM**

The ornamental design for the chair formed from continuous tubing, as shown and described.

DESCRIPTION

FIG. 1 is a front perspective view of the chair formed from continuous tubing showing my new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The line shading shown in FIGS. 1-7 is used to indicate shading and not a pattern on the material of the chair.

1 Claim, 4 Drawing Sheets
